UNITED STATES PATENT OFFICE

2,341,577

AIRSHIP

John D. Stewart, Teton, Idaho

Application May 6, 1942, Serial No. 441,951

1 Claim. (Cl. 244—27)

This invention relates to airships, aeroplanes and similar devices, and has for the primary object the provision of a device of this character which will have a maximum amount of carrying capacity, stability, durability and maneuverability and which may be economically manufactured and maintained in operation over long periods of time.

Another object of this invention is the provision of a rigid body designed to provide durability, stability and maximum carrying capacity and for travel in either direction of its longitudinal axis with a minimum amount of air resistance.

A further object of this invention is the provision of power driven rotary wings for the body which will act to sustain the body in flight and for the ascent and descent thereof in a substantially vertical plane and for the propulsion of said body forwardly and rearwardly, and also may be employed as brakes for checking or retarding the flight of the body.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating an airship or similar device constructed in accordance with my invention.

Figure 2 is a top plan view illustrating the device.

Figure 3 is a fragmentary longitudinal sectional view illustrating the rotary wings and the power drive at corresponding ends thereof.

Figure 4 is a transverse sectional view illustrating the direction of rotation of the wings.

Figure 5 is a side elevation illustrating one of the wings with power applied to one end thereof.

Figure 6 is a view similar to Figure 5 illustrating the application of power to the opposite end of the wing.

Referring in detail to the drawings, the numeral 5 indicates an elongated rigid body of substantially cigar shape having conical shaped ends 6 to permit said body when in flight to move horizontally and in opposite directions with a minimum amount of air resistance. The end portions 6 of the body are provided with windows 7, doors 8 and fins 9 on opposite sides thereof and secured to shafts 10 provided with controls

11 whereby said fins may be caused to assume various positions for the purpose of steering the body while in flight. Any suitable control may be provided for the fins whereby they may be independently adjusted into their various positions and also permit the fins at one end of the body to be oppositely operated for the purpose of steering the body to the right or left. The control for the fins as before stated, may be of any well known construction and located in either end or both ends in order that the pilot may steer the body in flight from whichever end is the advance end of the body when in flight.

Depending diverging struts 12 are secured to 15 the lower wall of the body, and have attached thereto elongated skis 13 provided with upturned ends 14 on which the body may rest while on the ground and will permit the body to move longitudinally on the ground in opposite directions with a minimum amount of ease.

A stabilizing fin 15 is secured to the top wall of the body and extends longitudinally thereof to assist in sustaining the body stabilized while in flight.

20 It will be seen that a body of the construction and shape described will provide a maximum amount of carrying capacity and will be capable of flight in either direction with a minimum amount of air resistance.

Opposite sides of the body between the end portions are shaped to form elongated longitudinally extending wells or channels 16 in which partly operate power driven rotary wings 17 each including an elongated hub formation 18 and radially extending flexible blades 19 each curved. The hub portions 18 of the wings are secured on shafts 20 of tubular formation journaled on elongated rods or bars 21 suitably secured in bearings 22 carried by the side walls of the body 5 at the ends of the wells or channels 16. Opposite ends of the shafts 20 are geared to shafts 23 journaled transversely of the body. A drive shaft 24 is geared to one of the shafts 23 and a drive shaft 25 is geared to the other shaft 23. The shafts 24 and 25 are equipped with clutches 26 for connecting and disconnecting said power shafts to a prime mover 27 arranged in the body. The control for the clutches 26 is indicated generally by the character 28. The control 28 may be of any conventional construction and the purpose thereof is to engage and disengage either of the clutches 26 whereby the drive shafts 24 and 25 may be either driven by the prime mover separately or simultaneously. This arrangement will

permit power to be delivered to both ends of the rotary wings simultaneously or to either end.

The control 28 for the clutches may be operated from either end portion of the body.

The drive mechanism of the rotary wings from the prime mover as described, will rotate the wings in opposite directions as indicated by the arrows in Figure 4 and when power is applied to both ends of the wings simultaneously said wings act to sustain the body in flight with a maximum amount of lifting power.

During the application of power to both ends of the wings, the blades thereof sustain their normal shape and curvature, as shown in Figure 4, in order that the blades may produce a maximum lifting power. With the wings rotated as specified, the body may be caused to ascend in a substantially vertical plane and its elevation controlled or governed by the speed of rotation of the wings. When the wings rotate in the direction indicated in Figure 4 by the arrows, the blades when outwardly of the walls or channels will have action upon the air so as to provide a maximum amount of lift to the body and when operating within the wells or channels will have the air restricted thereto so that said blades when within the channels or wells will only offer a minimum action to the body in a downward direction.

When power is applied to one or the other of the ends of the wings, the blades thereof acting against the air will be caused to each take on a twist or spiral pitch increasing the traction of the blade in the air to propel the body longitudinally in a selected direction within a horizontal plane so as to cause the body to travel horizontally while in flight at a maximum rate of speed.

It will be apparent that by being able to apply power to either end of the wings, will permit the driving of the body while in flight horizontally in either direction. Also while the body is in flight and traveling horizontally a reverse application of power to the end of the wings will bring about a braking or checking action of the longitudinal flight of the body due to the blades of the wings taking on a reverse twist or spiral.

The twist or spiral pitch taken on by the blades of the wings by application of power to one or the other of the ends of said wings is clearly illustrated in Figures 5 and 6 of the official drawings.

5 By referring to Figure 1 it will be seen that the fins 9 are secured to the shafts 10 closer to one end than the opposite end and that the shafts are journaled in the end portions of the body 5 so that said fins may be tilted upwardly and downwardly. Further, it will be noted in Figure 1 that the gear housings 30 are shaped to reduce air resistance by being set within recesses provided in the sides of the body with the outer walls of said housings taking on a curvature corresponding to the walls of the body. It will also be seen in Figures 1 and 3 that the ends of the blades of the rotary wings are rounded and that each blade is of elongated formation in order that it may have a maximum amount of action upon the air.

15 While I have shown and described the preferred embodiment of my invention, it will be understood that minor changes in construction, combination and arrangement of parts may be 20 made without departing from the spirit and scope of the invention as claimed.

Having thus described the invention, what I claim is:

30 In an airship, a rigid elongated body having wells in opposite sides thereof, rotary wings extending generally lengthwise of the wells and journaled on said body at opposite sides thereof for movement partly within and partly out of the well and each including a plurality of radially 35 extending elongated flexible blades each having an arcuate curvature extending transversely thereof, a power medium in said body, and means for delivering power to the ends of the wings simultaneously and whereby power may be delivered to either end of said wings to bring about flexing of the blades in combination with the air resistance thereagainst to cause said blades to assume a spiral pitch for the propulsion of the body longitudinally in either direction.
